CLAIM

The ornamental design for a sealing device for medicine container or medical apparatus, as shown and described.

DESCRIPTION

FIG. 1 is a front view of the sealing device for medicine container or medical apparatus of the present invention;

FIG. 2 is a plan view thereof;

FIG. 3 is a left side view thereof;

FIG. 4 is a right side view thereof;

FIG. 5 is a back view thereof;

FIG. 6 is a bottom view thereof;

FIG. 7 is a perspective view from the front side thereof;

FIG. 8 is a perspective view from the bottom side thereof;

FIG. 9 is a IX—IX cross-sectional view taken from FIG. 1 thereof;

FIG. 10 is a perspective view from the front side thereof;

FIG. 11 is a perspective view from the bottom side thereof; and,

FIG. 12 is a XII—XII cross-sectional view taken from FIG. 1 thereof.

The broken line showing of the bottle is included for the purpose of illustrating use and environment and forms no part of the claimed design.
